(57) CLAIM

The ornamental design for a type font, as shown and described.

DESCRIPTION

FIG. 1 is a face view of a type font showing my new design; and,

FIG. 2 is a face view thereof shown in a sample block of text. The sample block of the text of FIG. 2 is intended to provide a contextual image relationship between adjacent characters of the font and the specific text in the block of text does not form part of the claimed design.

The type font is available under the trademark ZAPFINO FORTE LT from Heidelberg Druckmaschinen AG.

1 Claim, 2 Drawing Sheets

abcdefghijklmnopqrstuvwxyzABCDEFGHIJKLMNOPQRSTUVWXYZ

Zagfino Forte LT Pro 41722 Bei jeder Schriftgestaltung wird der Grundcharakter eines Alphabets von einheitlichen Formmerkmalen der Buchstaben bestimmt.
